FIG. 4

FIG. 5

FIG. 2

FIG. 3

FIGURE 1 is a perspective view of a coin telephone shelf showing my new design;

FIGURE 2 is a front view of the coin telephone shelf;

FIGURE 3 is a side view of the coin telephone shelf taken from the right side of FIGURE 2;

FIGURE 4 is a plan view of the coin telephone shelf; and

FIGURE 5 is a section view taken along the line 5—5 in FIGURE 2 to illustrate more clearly the shape of the forwardly projecting portion at the top of the coin telephone shelf.

The broken line showing is for illustrative purposes only.

I claim:

The ornamental design for a coin telephone shelf, as shown and described.
